UNITED STATES PATENT OFFICE.

WALTER L. SIEWERS, OF WINSTON-SALEM, NORTH CAROLINA.

DESIGN FOR AN UNDERGARMENT.

43,788.

Specification for Design.

Patented Apr. 1, 1913.

Application filed December 7, 1912. Serial No. 735,538. Term of patent 14 years.

To all whom it may concern:

Be it known that I, WALTER L. SIEWERS, a citizen of the United States, residing at Winston-Salem, in the county of Forsyth and State of North Carolina, have invented a new, original, and ornamental Design for an Undergarment, of which the following is a specification, reference being had to the accompanying drawing, forming a part thereof.

The drawing is a perspective view of the garment seen from the front.

The garment shown in the accompanying drawing is composed of a tubular knit fabric 1 having the wales of the knitting running longitudinally of the fabric with cuts 2 projecting from opposite sides upon the

lines and curves shown with long narrow V-shaped cuts 3 and 4 at the front and back respectively, such front and back cuts being substantially equal in length and extending to a considerable distance below the lower limits of the cuts 2. The fabric of the body is extended in long graceful curved lines to form shoulder straps 5 with bindings 6 finishing the cuts 2 and a binding 7 finishing the cuts 3 and 4.

I claim—

The ornamental design for an undergarment as shown and described.

WALTER L. SIEWERS.
